UNITED STATES PATENT OFFICE

ALBERT CHAMPION, DECEASED, LATE OF FLINT, MICHIGAN, BY BASIL W. DE GUILHARD, OF FLINT, MICHIGAN, AND DETROIT TRUST COMPANY, OF DETROIT, MICHIGAN, EXECUTORS, ASSIGNEES TO A C SPARK PLUG COMPANY, OF FLINT, MICHIGAN, A CORPORATION OF MICHIGAN

SPARK PLUG

Application filed January 7, 1929. Serial No. 330,824.

This invention relates to spark plugs of the type employed on internal combustion engines.

Spark plugs of conventional design comprise an outer shell grounded on the cylinder block and carrying one of the electrodes, and an insulator core through which the other electrode extends, the upper end of the last mentioned electrode projecting above the top of the core and arranged for attachment of a current conducting wire. In order to concentrate the intensity of the spark across the gap at the contact points of the electrodes, and to cut down the possibility of short circuit or current jump between the terminal and shell it has been necessary to extend the insulator core for some distance beyond the top of the shell; the effectiveness of the insulator being dependent upon the length of its surface. However, in the event the surface of the insulator becomes wet or dirty, as sometimes occurs in use, the current will flash or travel over the surface instead of jumping at the contact points.

To reduce the tendency toward short circuiting or current travel between the terminal and shell is one of the objects of the present invention, which contemplates the use of a flash arrester comprising a collar of insulating material placed upon the core between the terminal and shell, having an annular flange, which serves to increase the effective surface of the core and also as a shield for keeping the core dry and clean.

The invention will be more clearly understood by reference to the accompanying drawing in which Figure 1 is a vertical sectional view of a spark plug on which a collar is secured in accordance with the present invention. Figures 2, 3 and 4 are detail perspective views partly in section, showing alternative forms of the collar, that shown in Figure 2 being of the type associated with the spark plug in Figure 1.

Referring to the drawing by reference characters, the numeral 1 indicates a shell having a dependent extension 2 which is screw threaded for engagement within an opening in the engine cylinder block leading to the combustion chamber. Carried by the

shell is an insulator core 3 of porcelain, quartz or other nonconducting material, through a central bore of which extends the current conducting wire or electrode 4, having a contact point at its lower end in spaced relation with the electrode 5 carried by the screw threaded extension 2, which space constitutes a spark gap across which the current normally flashes. At the upper end of the terminal 4 there is formed a screw threaded enlarged portion or stud 6 on which may be threaded a nut, so as to provide a binding post or connector for a current conducting wire. The collar 8 having an outwardly projecting annular web or flange 9 is secured upon the periphery of the core adjacent the top thereof. The collar preferably consists of rubber or other similar non-conducting material, and the hole or opening through the center of the collar has a diameter slightly smaller than that of the core, whereby the inherent elasticity of the collar holds it snugly about the core. Formed on the inside of the collar are a pair of ribs or beads 10, which are adapted to extend into a similar pair of peripheral grooves in the upper portion of the core 3, providing an interlock to hold the collar on the core.

The collar 12 shown in Figure 3, having an annular flange 13, is provided with a smooth interior surface 14 and is particularly intended for use with insulator cores that have smooth peripheral surfaces, as distinguished from the grooved type shown in Figure 1. If desired, the inner surface of the collar 13 may be slightly tapered to conform with the taper on the core 3. In Figure 4, the collar 16 has a downwardly and outwardly flaring portion 17 terminating in an annular rim 18, forming a cup-shaped sleeve which affords a more effective shield or cover to protect the core against water and dirt.

It will be understood that more than one collar may be used on a single spark plug if such is found desirable. For instance, the collar shown in Figure 3 could be placed midway down the core and beneath the collar 8 in Figure 1.

From the above description it will be apparent that the outwardly projecting web in-

terposed between the terminal and shell and extending through the path of mutual attraction, protects the core from rain and water and also increases the surface area over which the current must pass, thereby minimizing the possibility of a short circuit and serving to arrest flash over between the terminal and grounded shell.

What is claimed is:

- 5 1. A flash arrester for spark plugs and the like, comprising a collar of elastic insulating material having an annular outwardly projecting web and a central apertured hub provided with an internal bead that is adapted to extend in interlocked relation through the inherent elasticity of the collar into a corresponding peripheral groove of the spark plug part on which the collar is to be fitted.
- 10 2. For use as an accessory with a spark plug having an insulator core between a central electrode and an outer electrode shell and which core extends a considerable distance beyond the top of the shell to the terminal connection of the electrode and is provided adjacent its upper end with a peripheral groove, a spark flash arrester comprising an annular disc or the like of elastic insulating material provided with a central aperture of a diameter initially smaller than that of the core for fitting the disc on the core in snug engagement by reason of its inherent elasticity and an internal annular bead formed on the disc inside said aperture for interlocking and seating engagement within the peripheral groove at the top of the core.
- 15 3. In a flash arrester for use as an accessory with a spark plug having an insulator core between an internal electrode and an external electrode carrying shell and which core extends a considerable distance beyond the top of the shell to the terminal connector at the upper end of the electrode, and is provided adjacent its upper end with a peripheral groove, said arrester comprised of a plate-like member of elastic insulating material having a central hub to be expanded and snapped onto the upper end of the core, and characterized by an internal bead within the hub for projection into said peripheral groove of the core.
